M. P. SCHELL,
NON-REFILLABLE BOTTLE,
APPLICATION FILED DEC. 11, 1912.

1,095,360.

Patented May 5, 1914.

UNITED STATES PATENT OFFICE.

MAX P. SCHELL, OF SAN FRANCISCO, CALIFORNIA, ASSIGNOR TO CHRISTOPHER H. KOBICKE, OF SAN FRANCISCO, CALIFORNIA.

NON-REFILLABLE BOTTLE.

1,095,360.

Specification of Letters Patent.

Patented May 5, 1914.

Application filed December 11, 1912. Serial No. 736,135.

To all whom it may concern:

Be it known that I, MAX P. SCHELL, a citizen of the United States, residing at San Francisco, in the county of San Francisco and State of California, have invented new and useful Improvements in Non-Refillable Bottles, of which the following is a specification.

The object of the present invention is to 10 provide a cheap and simple non-refillable bottle of cheap construction while effective for the purpose desired.

In the accompanying drawing, Figure 1 is a vertical section of the upper portion of 15 a bottle equipped with my invention; Fig. 2 is a similar view of the same in an inverted position; Figs. 3 and 4 are cross sectional views on the lines 3—3 and 4—4 respectively of Fig. 1.

Referring to the drawing, 1 indicates the neck of a bottle to which my invention is applied. Within said neck is a casing 2 of a valve chamber, the lower portion 3 of which is cylindrical and formed at the bottom with an outwardly extending flange 4, spun around an apertured circular disk 6, said flange being contained within a groove 7 formed in the inner surface of the neck of the bottle, said casing being secured within 25 said neck by a ring 8, of absorbent material, saturated with cement. Secured to the center of said disk, and extending upwardly therefrom, is a stem 9, which stem enters a cylindrical socket formed in the center 30 of a frusto-conical valve 11, of cork or similar light material, the base of which valve, when resting upon said disk, completely closes the apertures 12 therein. Upon said valve rests a ball 13, of glass or 35 similar non-corrosive material, the casing having a spherical top to fit snugly around said ball. In the wall of said casing apertures 14 are formed by cutting the metal of the casing along three sides of a rectangle 40 and pressing the metal inward about the fourth or lowest side, as clearly shown in Fig. 1. The metal pieces forced inward thus serve as protectors, preventing the passage through said apertures 14, and access 45 to the valve of wires or other instruments. When the bottle is inverted, the ball 13 rolls to the spherical end of the retainer, and the valve slides upon the stem from the disk, so 50 that the liquid can pass through the apertures in the disk, around the larger end of

said valve, through the apertures 14, and out between the casing and the neck of the bottle.

A very important feature of my present invention resides in the fact that the valve 60 11 is made wholly of cork, and has no metallic parts attached thereto or movable therewith. Therefore it is very light, and consequently in pouring the liquid out of the bottle said valve vibrates very easily and 65 rapidly. If this valve were of considerable specific gravity, as when it has attached thereto metallic parts, as in my U. S. Patent No. 1,019,535, then the effect would be that, in pouring liquid from the bottle, very considerable suction would have to be produced in the bottle before the valve would be drawn by said suction back to its seat. When it would be so drawn to its seat it would not be dislodged therefrom by the 70 weight of the liquid. With my improved valve this is not the case, for, because of its being lighter than the liquid being poured out it is drawn toward its seat by a very slight suction, while it is surrounded by the 75 liquid being poured out, but, as soon as this liquid has left it, it is forced away from its seat by the liquid in the bottle, air passing by the valve into the bottle to reduce the suction in the bottle. Thus there is set up 80 a very rapid vibration of the valve, the movement from its seat being caused by the movement of the liquid and the motion toward its seat by the suction produced by the discharge of said liquid. But, on account 85 of the valve being very light, this vibration is produced easily, by only a slight difference in pressure in the interior of the bottle, and consequently the suction in the interior of the bottle is never sufficient to permanently 90 hold the valve to its seat. This would not be the case if the valve had metallic parts attached thereto, but the valve would remain off its seat until a sufficient suction was produced to draw it to its seat and when once 95 drawn it would be held tightly thereon. It is for this reason that I employ the stationary stem 9 by which the valve is guided in its vibration, instead of employing a metallic stem movable with the valve to guide it in 100 its vibration.

My improvement also permits of great economy in construction. In my former device of Patent No. 1,019,535, in which I employed a valve having a metallic plate as a 110

part thereof, the manufacture of said plate and the securing it to the buoyant part of the valve, was far too costly, and I can make a large number of my present valves at the same cost of a single one of the valves shown in my former patent. The present construction also permits of the valve seat having a large number of holes and therefore permits of a freer flow of the liquid.

10 It will be seen the means for preventing refilling are very effective and at the same time cheap and easily made.

I claim:—

- 15 1. In combination with the neck of a bottle, an apertured casing secured therein, an apertured disk secured thereto, a stem secured to, and extending upwardly from, the disk, a valve made wholly of cork slideable on said stem within the casing and arranged in its seated position to close the apertures in the disk, and a ball within the
- 20

casing and resting on the valve when in its seated position.

2. In combination with the neck of a bottle, an apertured casing secured therein, 25 an apertured disk secured thereto, a stem secured to, and extending upwardly from, the disk, a buoyant valve slideable on said stem within the casing and arranged, in its seated position, to close the apertures in the disk, 30 and a ball within the casing and resting on the valve when in its seated position, said casing having integral protectors, each protector extending inwardly from that side of the aperture which is nearest the valve. 35

In testimony whereof I have hereunto set my hand in the presence of two subscribing witnesses.

MAX P. SCHELL.
